UNITED STATES PATENT OFFICE.

CHRISTIAN H. SCHLUNDT, OF INDIANAPOLIS, INDIANA.

INTERCHANGEABLE STEAM CHEST AND VALVE.

1,349,787.

Specification of Letters Patent. Patented Aug. 17, 1920.

Application filed March 5, 1918. Serial No. 220,473.

To all whom it may concern:

Be it known that I, CHRISTIAN H. SCHLUNDT, a citizen of the United States, residing at Indianapolis, in the county of Marion and State of Indiana, have invented certain new and useful Improvements in Interchangeable Steam Chests and Valves, of which the following is a specification.

This invention has relation to steam engines, and has for an object to provide an improved steam chest and rotary valve, whereby, to provide relatively large ports and a valve capable of positive and quick action thereby increasing the efficiency of the engine.

Another object of the invention is to provide a steam chest and a valve of the character above described, embodying a new reversing valve operable by means of a lever, whereby, a movement of the lever in one direction will admit steam to the chest to cause operation of the engine in one direction, and a movement of the lever in the opposite direction will cause a reversal of operation.

A still further object of the invention is to provide a new and improved valve operating means for a steam chest valve, operable by steam or other fluid pressure where-by a greater flexibility of operation is obtainable; the improvement embodying means for varying the valve throw and for advancing or retarding the cut-off.

A still further object of the invention is to improve the form of valve shown in my abandoned application, filed May 25, 1910, and bearing the Serial Number 563,433.

In addition to the foregoing, this invention comprehends improvements in the details of construction and arrangement of parts, to be hereinafter described and particularly pointed out in the appended claims.

In the accompanying drawings, in which similar and corresponding parts are designated by the same characters of reference, throughout the several views in which they appear:

Figure 1 is a diagrammatic view illustrating the correlation of the various elements of my invention.

Fig. 2 is a view in plan of my valve operating means.

Fig. 3 is a section taken on the line 3—3 of the preceding figure.

Figs. 4 and 5 are transverse sections taken on the lines 4—4 and 5—5 of Fig. 2.

Fig. 6 is a view in section of my improved steam chest and valve.

Fig. 7 is a horizontal section taken on the line 7—7 of Fig. 6.

Fig. 8 is a similar view taken on the line 8—8 of said figure, and

Fig. 9 is a view in plan of the valve.

With reference to the drawings and particularly Figs. 6 to 9, 10 indicates a steam chest divided centrally by a partition 11 defining chambers 12 and 13. A plurality of radial, tapering openings 14 are formed adjacent the partition in the bottom plate of the chest at the right hand end thereof and in the chamber 12, a similar formation of openings being provided at the left hand end as indicated at 15. Similar openings are provided in the chamber 13 in the right and left hand ends as indicated at 16 and 17 respectively. A valve chamber 18 is formed beneath the partition to receive a valve 19 in the form of a disk, a stem 20 being extended through an opening in the partition for connection to and for operating the valve. A relatively large opening 21 is formed radially in the valve 19 at one side thereof, the same being flanked at each side by smaller openings 22. A second large opening 23 is provided at the opposite side of the valve and in a similar manner is flanked by smaller openings 24. It will be noted that in a closed position of the valve the openings 21 and 23 are lapped by the material of the bottom plate of the chest between adjacent openings 14 and 16, and 15 and 17. A port 25 is formed in the chest beneath the ports 14 and 16, common to them both and communicating with the right hand end of the engine cylinder 27, a similar port 26 being formed beneath the openings 15 and 17 for communication with the left hand end of the cylinder.

Turn plug valves 28 and 29 are seated in openings formed in the right and left hand ends of the partition 11 and are formed with transverse ports 30. The valve 28 is operable to establish communication between either chamber 12 or 13 with an exhaust port 31, while the valve 29 is for the purpose of controlling communication between either of said chambers and an intake port 32. The partition 11 is formed with a recess at each side of the valve stem 20 to receive 110

100 openings formed in the right and left hand ends of the partition 11 and are formed with transverse ports 30. The valve 28 is operable to establish communication between either chamber 12 or 13 with an exhaust port 31, while the valve 29 is for the purpose of controlling communication between either of said chambers and an intake port 32. The partition 11 is formed with a recess at each side of the valve stem 20 to receive 110

packing strips 33, and passages 34 are formed in the partition communicating at one end with the recesses above the strips and with a passage 35 in the valve 29 leading to the port 30 thereof, whereby, steam pressure may be constantly admitted to the recesses to retain the packing strips in engagement with the upper face of the rotary valve. An arm 36 is secured to each reversing valve 28 and 29, said arms being connected for operation in unison by means of a link 37. A link 38 is connected to one of the arms and to a reversing lever 39.

My improved valve operating means is shown in Figs. 1 to 5 and consists of the frame 40 formed with a pair of parallel, laterally extending arms 41, apertured to receive the rod 42. A rod 44 is mounted in the frame, parallel to the shaft but adapted for longitudinal movement therein. The rod 44 extends through a cylinder 45 and a piston movable in the cylinder and indicated at 46 is secured to the rod. Inlet and exhaust ports 47 and 48 are provided at opposite ends of the cylinder. Stop screws 49 are also mounted in the frame to engage the ends of the rod 44 to limit movement thereof.

An arm 50 is rigidly connected to the rod 44 at one end while the other end is bifurcated as at 51. A sleeve 52 is mounted on the shaft 42 and is formed at one end with an annular flange 53 formed with a circular series of apertures. A grooved collar 54 is mounted on the sleeve and the bifurcated end of the arm 50 is received in said collar. The rod 42 is formed for a portion of its length with a pair of keys 55, and a collar 56 is slidably mounted on the keyed portion 40 of the shaft, the keys permitting such movement but preventing rotative movement of the collar relative to the shaft. The exterior surface of the collar 56 is formed with a plurality of spirally arranged ribs 57 to enter complementary grooves 58 formed interiorly of the hub portion 59 of an eccentric 60. A plurality of slender rods 61 serve to connect the collars 54 and 56 to insure movement thereof in unison. The hub of the eccentric bears against the enlargement 53 at one end, while an adjustable collar 62 is mounted on the rod 42 to bear against the other end of the hub.

In use, the port 48 of the cylinder 45 of the valve operating mechanism is connected to the chamber 12 of the steam chest by means of a pipe 63, while the port 47 of the cylinder is connected to the chamber 13 of the chest by means of a pipe 64. An arm 65 is secured to the valve stem 20, and a link or eccentric rod 66 is connected at one end to the arm 65 and at its other end to the eccentric disk 60 by means of an eccentric strap.

65 In operation, and assuming the valves 28

and 29 to be in the relative positions shown in Fig. 7, steam will be admitted into the chamber 12 of the steam chest through the intake port 32 and valve 29. The steam will then enter either the openings 14 or the 70 openings 15, depending upon the position of the valve 19. Assuming the valve in question to be in a position to open the ports 15, steam will enter the same and the engine cylinder 27 to the left of the piston through 75 the port 26, thereby moving the piston to the right. Simultaneously with the admission of steam in the manner stated to the cylinder, a portion of the steam pressure will enter the pipe 64 and through the port 47 80 into the cylinder 45 of the valve operating mechanism at one side of the piston therein. The piston 46 will also be caused to move to the opposite end of the cylinder, and in so doing move the collar 54 along the rod 42, 85 whereby, by reason of the spiral connection of the collar 56 with the eccentric 60, to partially rotate the eccentric and thereby rotate the valve 19 of the steam chest to a position wherein the openings 15 and 16 will be 90 lapped, and the openings 14 and 17 unlapped. Steam will thus be permitted to flow into the engine cylinder at the one end thereof, to return the piston therein to the opposite end. An admission of pressure into 95 the pipe 63, and consequently an exhaustion through pipe 64, is thus occasioned to move the piston 46 of the valve operating cylinder to its former position, with a consequent re-actuation of the eccentric to effect an admission of pressure to the other end of the engine cylinder, and the foregoing operation is repeated.

It will be apparent that the steam may be cut-off at any point during the stroke of the 105 engine piston by adjusting the stop screws 49 to vary the travel of the rod 44; and the valve throw may also be varied by loosening the strap of the eccentric and rotating the disk therein. Other uses and advantages of 110 my invention will readily occur to those skilled in the art to which this invention appertains.

While I have illustrated and described my invention with some degree of particularity, 115 I realize that in practice various alterations therein may be made. I therefore reserve the right and privilege of changing the form of the details of construction or otherwise altering the arrangement of the correlated parts, without departing from the spirit of 120 the invention or the scope of the appended claims.

Having thus described my invention, what I claim as new and desire to secure by Letters Patent is:

1. A valve gear comprising a frame, a rod slidably mounted therein, a cylinder mounted thereon, a piston mounted on the rod and slidably received in the cylinder, 130

means for admitting fluid pressure to the cylinder at the opposite sides of the piston, an arm carried by the rod, a second rod journaled on the frame, a collar carried by the 5 second mentioned rod and engaged at the arm, a second collar slidably mounted on the last mentioned rod and constrained to rotate in unison with the same and connected with the first mentioned collar, a hub receiving 10 the second mentioned collar, cam slot and groove connections between the hub and second mentioned collar, an eccentric mounted on the hub and a rod operatively connecting the eccentric with the valve.

15 2. In a valve gear a rod journaled for rotation, a collar mounted thereon, means

for shifting the collar on the rod, a second collar slidably mounted on the rod and constrained to rotate in unison therewith, means operatively connecting said collars together, 20 a hub receiving the second mentioned collar, cam slot and groove connections between the second mentioned collar and the hub, an eccentric mounted on the hub and means operatively connecting the eccentric with the 25 valve.

In testimony whereof I affix my signature in the presence of two witnesses.

CHRISTIAN H. SCHLUNDT.
